UNITED STATES PATENT OFFICE.

BENJAMIN F. KLEIN, OF CLEVELAND, OHIO.

DESIGN FOR A COMBINATION LIGHTING FIXTURE AND SUPPORT FOR LOUD-SPEAKER UNITS.

Application filed September 29, 1928. Serial No. 28,323. Term of patent 14 years.

To all whom it may concern:

Be it known that I, BENJAMIN F. KLEIN, a citizen of the United States, residing at Cleveland, in the county of Cuyahoga and State of Ohio, have invented a new, original, and ornamental Design for a Combination Lighting Fixture and Support for Loud-Speaker Units, of which the following is a specification, reference being had to the accompanying drawing, forming part thereof, wherein—

Fig. 1 is a view in front elevation of a fixture disclosing my new design; Fig. 2 is a top plan view disclosing the details of the support for the loud speaker unit and Fig. 3 is a top plan view of the base of the fixture.

I claim:—

The ornamental design for a combination lighting fixture and support for loud speaker units, as shown.

BENJAMIN F. KLEIN.
